COMBINED CANDLE AND FLOWER HOLDER

John P. Myers, 1435 S. La Cienega Blvd., and John L. McCarthy, 1438 S. La Cienega Blvd., both of Los Angeles, Calif.

Filed Aug. 24, 1964, Ser. No. 81,411

Term of patent 14 years

(Cl. D48—2)

We claim:

The ornamental design for a combined candle and flower holder, substantially as shown.
